DESIGN FOR A FLAME PAD

Isaac D. Richheimer, New York, N. Y.

Application July 12, 1934, Serial No. 52,556

Term of patent 7 years

To all whom it may concern:

Be it known that I, Isaac D. Richheimer, a citizen of the United States and a resident of New York, in the county of New York and State of New York, have invented a new, original, and ornamental Design for Flame Pads, of which the following is a specification, reference being had to the accompanying drawing, forming part thereof.

Figure 1 is a top plan view of a flame pad showing my new design.

Figure 2 is a side elevational view thereof, Figure 3 is a bottom plan view of the pad, and Figure 4 is a transverse vertical sectional view through the flame pad.

I claim:

The ornamental design for a flame pad as shown.

ISAAC D. RICHHEIMER.
